DESIGN FOR A RUBBER OVERSHOE

Emil Gottschalk, New York, N. Y., assignor to Gem Rubber Corporation, New York, N. Y.

Application May 23, 1946, Serial No. 130,011

Term of patent 7 years

(Cl. D7—4)

To all whom it may concern:

Be it known that I, Emil Gottschalk, a citizen of the United States of America, residing at New York, in the county of New York and State of New York, have invented a new, original, and ornamental Design for Rubber Overshoe, of which the following is a specification, reference being had to the accompanying drawing, forming part thereof.

Fig. 1 is a side view of a rubber overshoe, showing my new design,

Fig. 2 is a top view of the same, and

Fig. 3 is a sectional view taken on the line 3—3 of Fig. 1.

I claim:

The ornamental design for a rubber overshoe, as shown.

EMIL GOTTSCHALK.
